UNITED STATES PATENT OFFICE.

ALLEN A. HORTON, OF HIGHLAND PARK, MICHIGAN, ASSIGNOR TO BURROUGHS ADDING MACHINE COMPANY, OF DETROIT, MICHIGAN, A CORPORATION OF MICHIGAN.

ADDING-MACHINE.

1,359,173.

Specification of Letters Patent. Patented Nov. 16, 1920.

Application filed December 26, 1916. Serial No. 138,916.

To all whom it may concern:

Be it known that I, ALLEN A. HORTON, a citizen of the United States, residing at Highland Park, in the county of Wayne and State of Michigan, have invented certain new and useful Improvements in Adding-Machines, of which the following is a specification.

This invention relates to adding machines of the kind which have automatic means whereby to perform subtraction by the process of complemental addition. There are several known ways of accomplishing such a result, one such arrangement employing a rotating drum having complementally related series of spirally-arranged stop-pins, and another employing complementally arranged shiftable couplings between the numeral keys and the stops which measure movements of registering elements, and still another known arrangement employing stepped stop-plates in conjunction with keys each of which has two stop-pins for co-operation with such plates, one of the latter being permanently connected with a type-carrier and separably engaged with a registering rack bar, and the other stepped plate adapted to be connected with and disconnected from said rack bar. The two first mentioned arrangements have been known heretofore as applied to the so-called "10-key" type of adding machine, and the third-mentioned arrangement as applied to the so-called "81-key" type of adding machine. My invention has more especial reference to the latter type of adding machine and I aim to attain certain practical advantages in adapting such a machine for performance of subtraction by the process of complemental addition, among which advantages are the maintenance of a permanent connection between the registering rack bars and the type-carriers, and the avoidance of any coupling and uncoupling of indexing devices (which term embraced the value keys and settable stops which measure the movements of the registering bars and type-carriers both for straight work of addition and for work of subtraction by complemental addition.) I am able to accomplish the desired results by comparatively simple mechanical means, in which connection I may mention the fact that I employ only a single stop on a registering bar, for each of the two sets of key-

stops which I use, and I may add that the two stops are on a single piece. As just indicated I employ two sets or series of key-stops, one of which serves in straight addition and the other in complemental addition. While this means the employment of sixteen separate and independently movable stops for each row of keys, nevertheless my invention does not involve the employment of a great multitude of mechanical parts, for besides being able to accomplish the desired result with a single stop-piece on each registering bar, as above mentioned, I require but four intervening parts between the eight keys and the sixteen stops whereby to set the latter. In this connection it may be well to point out here that each of said keys simultaneously sets two stops, one of each set, such two stops being complementally related. For example, depression of the 2-key sets the 2 stop for addition and the 7 stop for subtraction, though of course only one of a pair of said stops will function in the same operation. Whether it is the addition or subtraction stop will depend upon the setting of the stop-piece of the registering bar.

As before stated, the registering bars are permanently connected with the type carriers. In order to provide for always printing the number corresponding with the key that is depressed, whether addition or subtraction is being performed, I provide each type carrier with a double set of types, and the two sets run reversely and their individual members are alternated. Thus the types for printing added amounts run as usual from top to bottom of the type carrier, whereas the types for printing subtracted amounts run from bottom to top, there being a cipher type at each end of the type-carrier in order to provide for the filling in of ciphers to the right of the highest significant digit either in an added amount or in a subtracted amount. With such an arrangement of alternating addition and subtraction types it is of course necessary to regulate the type-carrier to suit the work in hand, and according to my present disclosure I mount the type-carrier on a shifting pivot and so connect it with the stop-piece of the associated registering bar that the shifting of the type-carrier pivot effects the proper setting of that stop-piece.

The above reference to the filling in of ciphers suggests adherence to the most common commercial form of printing mechanism in adding machines, to wit, that which does not require the use of any cipher keys but which provides for automatically supplying ciphers whenever called for while avoiding the appearance of any ciphers in the printed amount to the left of the highest significant digit. Now in adapting such character of printing mechanism to the uses of an adding machine equipped for the performance of subtraction by the process of complemental addition, I provide for elimination of ciphers to the left of the highest significant digit of a subtracted amount. It will be understood that when performing subtraction type-carriers in all orders to the left of that in which the highest significant digit is to be printed, will partake of the maximum movement, in view of the fact that in such orders it is necessary to add 9's to the registration. Such maximum movement brings the cipher types at the bottom of the type-carriers to the printing line, and then there will come into play the special means I provide for preventing such types from being struck. Of course the same thing happens in those lower orders where ciphers occur in the subtrahend but there the ciphers should be printed and they are by reason of cooperative relationship between latches or triggers which control the printing hammers in a familiar manner.

The double series of types in reverse order and alternating position, as above referred to, provides for the 9's of the subtraction series being normally at the printing line under a subtraction setting of the type-carriers. Therefore the 9-keys work special stops which serve to prevent any movement of rack bars and type-carriers in orders where 9 occurs in the subtrahend.

In the accompanying drawings which illustrate the preferred form of embodiment of my invention, Figure 1 shows the interior mechanism of the machine in right side elevation and the inclosing casing and numerous cross-rods and shafts in section, the condition illustrated being normal with parts set to perform straight addition; Fig. 1^a shows the units and tens type-carriers on an enlarged scale in rear elevation; Fig. 2 is a view similar to Fig. 1 but here a vertical section line is followed which cuts off half of the key-stop-setting devices of the group belonging to the illustrated row of keys, and also cuts off the entire units order of registering and recording devices. In this view, as in Fig. 1, the machine is set for straight addition, but unlike Fig. 1, parts are shown out of normal, to wit, with the 3-key depressed and the operating handle forward. Fig. 3 is a somewhat similar view on a larger scale and not embracing as many

parts, and further differing from Figs. 1 and 2 in that the machine is set for performing subtraction, the 4 key being down and other parts out of normal as a result of pulling the operating handle forward. In this view, as in Fig. 1, the stop-setting devices of the illustrated group of keys appear in right side elevation. Fig. 4 shows stop-setting devices and stops after the manner of Fig. 2; Fig. 5 is a vertical cross-section looking from the front, the section line being stepped so as to take in the stop of the 4-key of the units row (which stop is shown set), the stop of the 3-key of the tens row, the stop of the 2-key of the hundreds row, and the stop of the 1-key of the thousands row,—a four-bank machine being illustrated as a matter of convenience and economy of space; Fig. 6 is a fragmentary illustration of parts which appear at about the middle of Fig. 1 and illustrates the effect of depressing the 9-key; Fig. 7 is a fragmentary perspective view further illustrating the 9-key stop construction; Fig. 8 shows the system of actuating devices as connected with the operating handle, the machine itself being merely indicated in outline.

Inasmuch as the present invention is chiefly concerned with indexing or amount-determining means and with recording means, I have largely confined the illustration in the accompanying drawings to those things, and I have thought it sufficient to conventionally illustrate registering mechanism without showing details thereof. Likewise I have illustrated the roller platen conventionally without showing paper-holding and feeding mechanism or inking ribbon. The numeral wheels 12 are located at the front of the machine under a lowered portion of the machine casing 13 in which suitable sight openings 13^a are provided, and pinions 12^a fastened to the numeral wheels coöperate with racks 14^a on slide bars 14. The numeral wheels and pinions are carried in a rocking frame 12^b which may be controlled in any suitable manner to properly regulate engagement between the pinions and the racks.

A description of one group of indexing or stop devices will suffice for all as they are duplicates of each other, except for an extra spacing in the units order which takes care of the familiar necessity for making the subtraction complement the difference between ten and the units digit of the subtrahend, instead of nine as in all other orders.

Proceeding then to a description of a typical group of indexing devices, A designates the keys themselves which stand in a row as usual and bear numerals from 1 to 9, said keys being independently depressible through slots in the keyboard panel plate and coöperating with appropriate detent

- and locking devices hereinafter described, and also coöperating, in a novel manner, with certain stops which determine the extent of movement of the associated rack bars
- 5 14 which, as customary in these machines, is drawn rearward by a spring 14^b. The stops above referred to are in the form of blades and they are divided into two sets or series, one located forward and the other rearward,
- 10 14 which, as customary in these machines, is drawn rearward by a spring 14^b. The stops above referred to are in the form of blades and they are divided into two sets or series, one located forward and the other rearward,
- 15 14 which, as customary in these machines, is drawn rearward by a spring 14^b. The stops above referred to are in the form of blades and they are divided into two sets or series, one located forward and the other rearward,
- 20 14 which, as customary in these machines, is drawn rearward by a spring 14^b. The stops above referred to are in the form of blades and they are divided into two sets or series, one located forward and the other rearward,
- 25 14 which, as customary in these machines, is drawn rearward by a spring 14^b. The stops above referred to are in the form of blades and they are divided into two sets or series, one located forward and the other rearward,
- 30 14 which, as customary in these machines, is drawn rearward by a spring 14^b. The stops above referred to are in the form of blades and they are divided into two sets or series, one located forward and the other rearward,
- 35 14 which, as customary in these machines, is drawn rearward by a spring 14^b. The stops above referred to are in the form of blades and they are divided into two sets or series, one located forward and the other rearward,
- 40 14 which, as customary in these machines, is drawn rearward by a spring 14^b. The stops above referred to are in the form of blades and they are divided into two sets or series, one located forward and the other rearward,
- 45 14 which, as customary in these machines, is drawn rearward by a spring 14^b. The stops above referred to are in the form of blades and they are divided into two sets or series, one located forward and the other rearward,
- 50 14 which, as customary in these machines, is drawn rearward by a spring 14^b. The stops above referred to are in the form of blades and they are divided into two sets or series, one located forward and the other rearward,
- 55 14 which, as customary in these machines, is drawn rearward by a spring 14^b. The stops above referred to are in the form of blades and they are divided into two sets or series, one located forward and the other rearward,
- 60 14 which, as customary in these machines, is drawn rearward by a spring 14^b. The stops above referred to are in the form of blades and they are divided into two sets or series, one located forward and the other rearward,
- 65 14 which, as customary in these machines, is drawn rearward by a spring 14^b. The stops above referred to are in the form of blades and they are divided into two sets or series, one located forward and the other rearward,
- high order rack bars in order to take care of the necessity already alluded to. This is done by the simple expedient of locating said stop projection 15^a one step farther forward on its rocking arm than the stop projections 15^c of higher order rocking arms. This is clearly illustrated in Figs. 1 and 6.
- The central pivotal mounting of the rocking arm upon the rack bar provides for the setting of that arm so as to either have the 75 stop-blades of the forward series project into the path of the adding stop projection 15^b, or the stop-blades of the rearward series project into the path of the projection 15^c, or 15^a in the case of the units wheel. I shall 80 not for the present describe the means for setting the rocking arm because that is done through connection with the type-carrier, and it will therefore be better to leave this until I come to a description of the printing 85 mechanism.
- It will be noted that in Fig. 1 the zero stop-blade F confronts the stop-projection 15^b ready to prevent movement of the rack bar if the machine is operated with no key 90 depressed (there is just a slight clearance space to prevent binding). Here the adding condition is illustrated and the depression of any one of the keys will result in lifting said zero stop-blade and lowering one of the 95 stop-blades B into the path of the projection 15^b, as illustrated in Fig. 2, where the 3-key is down and the corresponding stop-blade is engaged with the said projection 15^b, the operating handle 17 being forward. 100 Rocking the arm to the other or subtraction position takes the projection 15^b below the zero stop-blade F and locates the rear projection 15^c (or 15^a) for coöperation with the special stop-blade G or any one of the eight 105 stop-blades C or with the fixed stop-blade E.
- It should be understood at this point that where there is a cipher in the subtrahend and therefore no key in that order is depressed, there must not be prevention of 110 movement of the rack bar as by the zero stop F under adding conditions, but on the contrary the rack bar should move to the maximum extent so that nine will be complementally added in any order except the 115 units order and ten will be added in the latter order. Hence the setting of the rocking arm for subtraction does not put the projection 15^c (or 15^a) right in front of any stop-blade but simply puts it where it will strike 120 against the most remote stop-blade of the rearward series, to wit, the fixed blade E, as illustrated in Fig. 3. The situation which calls for preventing any movement of a rack bar is that wherein a 9 occurs in the subtrahend elsewhere than in the units order, for the complement in such case is zero. Therefore depression of the 9-key drops the special stop-blade G directly behind the stop-projection 15^c, as illustrated in Fig. 6. 125 130

In the units order there should be a one-step movement of the rack bar in such a situation and it will be noted that the units stop-projection 15^a in Fig. 6 is spaced one 5 step from the lowered stop-blade 7.

As before stated, the movable stop-blades B and C of the two series have their members connected in pairs with the keys numbered 1 to 8, and this of course is done complementally. Thus the 1-stop-blade of the forward series and the 8-stop-blade of the rearward series are adapted to be simultaneously set by depression of the 1-key, and the 2-stop-blade of the forward series and 10 the 7-stop-blade of the rearward series are adapted to be simultaneously set by depression of the 2-key, and so on. This is accomplished through the employment of four cam bars or plates, each of which is operable 15 by either of two complementally paired keys but in opposite directions, and is formed with two pairs of reversely related key-setting cam-slots. Thus one of these plates is shifted in one direction by the 1-key and 20 in the opposite direction by the 8-key, and another one of these plates is shifted in one direction by the 2-key and in the opposite direction by the 7-key, and the third is shifted in one direction by the 3-key and in 25 the opposite direction by the 6-key and the fourth is shifted in one direction by the 4-key and in the opposite direction by the 5-key.

Referring to Figs. 1 to 3, the numeral 18 30 designates the cam-bar or plate which is operated by the 1 and 8-keys. The flat stems A¹ and A⁸ of those keys extend down alongside said bar or plate and in widened portions of said stems there are formed cam-slots a¹ and a⁸ into which project studs 18^a 35 and 18^b on the bar. Each cam-slot comprises a horizontal branch and an oblique branch and the slots are reversely related to each other so that when the 1-key is depressed the cam-bar will be forced rearward, the stud 18^b then riding idly in the horizontal branch of the slot of the 8-key stem, and when the 8-key is depressed the said bar will be forced forward, the stud 40 18^a riding idly in the horizontal branch of the slot of the 1-key stem. A cam-slot 18^c is formed in the lower forward portion of 45 said bar and embraces a lateral projection b, on the 1-stop-blade of the forward series. 50 A similar cam-slot 18^d formed in the rear portion of said bar embraces a lateral projection c on the 8-stop-blade of the rear series. The oblique portions of these two cam-slots in the bar extend downwardly 55 and forwardly from horizontal branches of the slots so that when the bar is forced rearward by depression of the 1-key both the 1-stop-blade of the forward series and the 8-stop-blade of the rear series will be lowered. 60 65

Now there are two other cam-slots 18^e and 18^f in this same bar and they are similar in form to the cam-slots 18^a and 18^d but reversed as compared therewith, that is to say, their oblique portions extend rearwardly 70 instead of forwardly. The cam-slot 18^e embraces a lateral projection on the 8-stop-blade of the forward series and the cam-slot 18^f embraces a lateral projection on the 1-stop-blade of the rear series. Consequently when the 8-key is depressed and the bar thereby thrust forwardly the 8-stop-blade of the forward series will be lowered 75 and the 1-stop-blade of the rear series.

Immediately above the cam-bar 18 and in 80 the same plane therewith is a cam bar 19 which is operated by the 4 and 5-keys. The flat stems A⁴ and A⁵ of these two keys extend down past said cam-bar and in widened portions of these stems there are 85 formed cam-slots a⁴ and a⁵ just like the cam-slots of the 1 and 8-key stems, which cam slots a⁴ and a⁵ embrace studs 19^a and 19^b on the bar 19 so that when the 4-key is depressed said bar is forced rearwardly and 90 when the 5-key is depressed said bar is forced forwardly. A cam-slot 19^c at the upper forward portion of the bar 19, and just like the cam-slot 18^e of the bar 18, embraces a lateral projection on the 4-stop-blade of 95 the forward series, and a similar slot 19^d at the lower rear portion of said bar 19 embraces a lateral projection on the 5-stop-blade of the rear series, so that when the bar is forced rearward by depression of the 100 4-key these two stop-blades will be lowered, as shown in Fig. 3. Another pair of cam-slots 19^e and 19^f in this bar 19 embrace respectively lateral projections upon the 5-stop-blade of the forward series and the 105 4-stop-blade of the rear series so that when the 5-key is depressed and the bar thrust forward these two stop-blades will be lowered.

The two cam-bars above identified are located at the right of the stop-blades, as shown in Fig. 5. The two other cam-bars of the set of four are located at the left, one above the other. The lower one of these left-hand cam-bars, appearing in side elevation 11 in Figs. 2 and 4, is designated 20 and is operated by the 3 and 6-keys whose flat stems A³ and A⁶ extend down alongside the bar and have cam-slots a³ and a⁶ in their widened portions embracing studs 20^a and 110 20^b on the bar. These cam-slots are of the same character as those in the stems of the 1 and 8 and 4 and 5-keys so that when the 3-key is depressed the bar 20 is forced rearward and when the 6-key is depressed said bar is forced forward. This cam-bar 20 operates with the 3-stop-blade of the forward series and the 6-stop-blade of the rear series and also with the 3-stop-blade of the rear series and the 6-stop-blade of the for- 125 130 135

ward series, in the same manner that the before-described cam-bars 18 and 19 coöperate with their stop-blades of the two series, but the slot-design in the bar 20 is a little 5 different. Thus there is a continuous slot at the front part of the bar embracing the lateral projections on the 3 and 6-stop-blades of the forward series, and a continuous slot in the rear portion of the bar embracing the 10 lateral projections on the 3 and 6-stop-blades of the rear series. This, however, is a mere matter of expediency in manufacture and these two continuous slots are in effect 15 two pairs of slots, the front half 20^a of the forward slot and the back half 20^b of the rear slot constituting one pair, and the back half 20^a of the front slot and the front half 20^b of the rear slot constituting the other pair. It will be seen therefore that when 20 the 3-key is depressed and the bar 20 thrust rearward the 3-stop-blade of the forward series and the 6-stop-blade of the rear series will be lowered; whereas when the 6-key is depressed and the bar thrust forward the 25 6-stop-blade of the forward series and the 3-stop-blade of the rear series will be lowered.

The remaining cam-bar 21 is arranged 30 immediately above the bar 20 and is operated by the 2 and 7-keys whose flat stems A^a and A^b extend alongside said bar and have cam slots a^a and a^b embracing studs 21^a and 21^b on the bar so that when the 2-key is depressed the bar is thrust rearward and when 35 the 7-key is depressed the bar is thrust forward. A cam slot 21^a in the forward portion of the bar 21 embraces a lateral projection on the 2-stop-blade of the forward series, and a similar cam-slot 21^b in the 40 rear portion of the bar embraces a lateral projection on the 7-stop-blade of the rear series. A reverse cam-slot 21^b in the forward portion of the bar embraces a lateral projection on the 7-stop-blade of the forward series and a similar cam-slot 21^a in the 45 rear portion of the bar embraces a lateral projection on the 2-stop-blade of the rear series. Thus when the 2-key is depressed and the bar thrust rearward the 2-stop-blade of the forward series and the 7-stop-blade of the rear series are lowered, whereas 50 when the 7-key is depressed the 7-stop-blade of the forward series and the 2-stop-blade of the rear series are lowered.

55 From the above it will be clear that the eight keys operate the successive stop-blades of the forward series so as to properly measure the movement of the rack bar according to the value of the key depressed 60 when addition is being performed. It will also be clear that a complementary stop-blade of the rear series is always lowered as an accompaniment to the lowering of the stop-blade of the forward series. Consequently 65 if the stop-arm 15^b on the rack bar is set for

subtraction the movement of the said rack bar will be complementally measured. For instance, as illustrated in Fig. 3, (where the 4-key is shown depressed and the cam bar 19 thrust rearward, lowering the 4-stop-blade of the forward series and the 5-stop-blade of the rear series), the forward projection 15^b of the stop-arm 15 (the one nearest the observer) passes below said 4-stop-blade and the movement of the rack 75 bar is measured by abutment of the rear stop projection 15^a against the lowered 5-stop-blade of the rear series. In this same illustration no key has been depressed in the next higher order and consequently the rack 80 bar of that order partakes of the maximum movement as measured by abutment of the rear stop-projection 15^a against the fixed stop-blade E.

The four cam-bars or plates 18, 19, 20 85 and 21 are supported by and slide through guiding slots in the before-mentioned vertical plate 16 and another vertical plate 16^a at the front, and the key-stems and the stop-blades are properly held and guided in slots 90 in two horizontal plates 16^b and 16^c rigidly secured to the plates 16 and 16^a. The key-stems are offset as best shown in Fig. 5, so as to provide for the stems of the 1, 4, 5 and 8-keys extending down past the right-hand sides of the cam-bars 18 and 19, and for the stems of the remaining keys passing down along the left-hand sides of the other two cam-bars 20 and 21. Springs 22 normally uphold the keys, said keys being conveniently attached to ears on the lower portions of the key-stems and being anchored in the upper horizontal plate 16^c.

The lifting of the zero stop-blade F whenever any key is depressed is provided for in 105 the following manner: In an upper portion of said blade projecting sufficiently above the frame plate 16^c, there is formed an opening into which projects one arm of a small bell-crank lever 23 pivoted to an ear of the 110 plate 16^a. The other arm of said bell-crank lever is pivoted to a detent strip 24 which extends alongside the entire series of key-stems and slides through slots in the vertical frame-plates 16 and 16^a. This detent 115 strip is formed with a series of short spaced flanges to coöperate with the key-stems whereby to effect the lifting or withdrawal of the zero stop-blade and also the latching down of the depressed key and the locking 120 out of the rest of the keys. The foremost flange 24^a functions only in the first two-mentioned respects and the rearmost flange 24^b functions only to lock out the 9-key. The remaining flanges 24^c function in all 125 three respects. Each key-stem has a forward projection 25 with an inclined under edge to coact with the beveled rear edge of the adjacent flange of the detent strip for the thrusting forward of the latter and con- 130

sequent lifting of the zero stop. A small shoulder 26 is formed in the upper part of the projection 25 for said flange of the detent strip to engage when the key is fully depressed whereby to hold it down, as best shown in Fig. 3 where the 4-key is in action. A spring 24^a applied to the detent strip brings this about and of course it will be understood that the rearward movement 10 of the strip to engage its flange with the said shoulder is insufficient to again lower the zero stop into the path of the stop-projection 15^a on the stop-arm of the rack-bar.

On the rear side of each key-stem there 15 is formed a projection 27 with an inclined upper side to coact with the beveled forward edges of flanges of the detent strip so that the power of the key-spring may be availed of to aid the spring 24^a in restoring 20 the detent strip when the key rises. The under edges of these projections 27 are abrupt and when a key is depressed the flanges engage beneath the projections of unoperated keys and thereby lock them out, 25 as illustrated in Fig. 3. The detent strip 24 projects in rear of the frame-plate 16 sufficiently to be operated upon by an automatic key-releasing device at the termination of an operation of the machine, the particulars 30 of which action will be pointed out later on in connection with a description of certain actuating devices worked by the operating handle 17.

With respect to the indexing devices it re- 35 mains to describe the arrangement for lowering the special stop-blade G when the 9-key is depressed, said blade functioning, as before stated, to prevent movement of the rack-bar when performing subtraction, ex- 40 cept as to the units rack-bar which in such case partakes of a one-step movement. Of course it will be understood from what has already been described that the 9-key has no connection with any one of the double- 45 acting stop-bars for it is quite unnecessary to set a key-stop to measure the maximum movement of the rack-bar in performing addition. The fixed stop-blade D functions in that respect. It is essential, however, in the 50 case of subtraction to set a stop representing the complement of 9 when the 9-key is depressed. This is very simply accom- 55 plished, as best shown in Figs. 6 and 7, by supplying the 9-key-stem A^a with a later- ally projecting finger a^a at the offset portion of said stem, and having that finger engage in a square notch d cut in the edge of an upwardly projecting portion of the blade G.

Passing now to the recording mechanism 60 of the machine, duplicate type-carriers and printing devices are employed for all of the orders except the units order, so that a description of one complete set will suffice for all and this applies also as to the units order 65 save for the type-housing being extended

and the subtraction types located a step lower than upon the other type-carriers and a certain controlling lever being longer. There is a type-carrying lever of bell-crank form mounted upon a pivot rod 50 which 70 occupies short vertical slots 51 in the supporting side plates or frame-pieces of the machine. One branch 52 of this bell-crank lever normally extends downward and forward and is pivoted to the upturned rear 75 end of an extension 15^a of the pivoted stop-arm 15 on the rack bar. The other arm 52^a of this bell-crank lever normally extends rearwardly and downwardly and it carries the arc-shaped housing 53 for the types. 80 There are two sets of types, nine in each set and the types of the two sets alternate in reversed order, as best shown in Fig. 1^a. The types which serve for the printing of added amounts are designated x and the 85 series begins with the cipher type at the upper end of the housing and it terminates with the 9-type. The subtraction set of types, designated y, begins with the cipher type at the bottom of the housing and ends 90 with the 9-type at the upper end so that this 9-type comes next to the cipher type of the addition series and then comes the 1-type of that series, and so on, in alternation. As the units rack-bar always moves an extra 95 step farther in subtracting operations as compared with other rack-bars, the housing for the units order types is made some- what longer so that it projects farther downward to accommodate the cipher type 100 of the subtraction series a step lower than the cipher type of the subtraction series of the tens type-carrier, as clearly illustrated in Fig. 1^a, and of course the other types 105 of the subtraction series in the units order are correspondingly lower down and there are no types between the 0 and 1-types of the subtraction or the addition series in the units order.

It will be manifest that the rack-bar 110 spring 14^a when drawing the rack-bar rear- ward will swing the bell-crank type-carry- ing lever about its pivot-rod 50 and of course the spacing apart of the types of each series corresponds with the spacing apart 115 of stop-blades of corresponding series so that the proper type will be brought to the printing line. The pivot-rod 50 normally occupies the bottoms of the short slots 51 and the cipher types of the addition series 120 are at the printing line, as illustrated in Fig. 1, properly positioned to be driven against the roller platen 60. Lifting of the pivot-rod 50 to the top of the slots will bring the 9-types of the subtraction series to the print- 125 ing line, except in the case of the units type- carrier. Manifestly, such lifting of the said pivot-rod will raise the rear end of the rack- bar stop-arm 15 rocking the same on its pivot 15^a. In this way the proper setting 130

of the type-carriers for subtraction is brought about simultaneously with the proper setting of the rack-bar stop-arms. It will be noted that the stop-blades vary somewhat in length so as to make the lines along which their lower ends terminate accord with the arcuate paths of the projections 15^b and 15^c resultant from their pivoted stop-arm being connected to the bell-crank lever.

The proper control of the pivot-rod 50 and the shifting thereof between addition and subtraction positions is provided for by having the ends of the rod project into cam-slots of a pair of arms 54 and 54^a which are secured to and extend vertically from stub-shafts 55 in bearings on the two side frames of the machine, said stub-shafts being rigidly connected by a yoke 56 allowing room for the type-carriers to swing. The left-hand arm 54^a is extended to serve as a handle projecting above the casing of the machine. When this handle is forward as shown in Figs. 1, 2 and 8, the rear ends of the cam-slots hold the pivot-rod in the bottoms of the short slots 51 and thus the adding condition is established and maintained. When the handle is thrown rearward, the said pivot-rod is moved to the upper ends of said slots 51 and there maintained, as shown in Fig. 3, which of course establishes the subtracting condition.

Referring next to the means for driving the types in printing, 61 designates a hammer pivoted upon a cross-rod 62 and having a cam-slot engaged by a stud on a hammer-driving-lever 63 which is pivoted upon a rock-shaft 64. A spring 65 is applied to this lever and a bail cross-rod 66 normally holds the lever retracted and the spring under tension. A latch or trigger 67 pivoted upon a cross-rod 68 normally engages over the forwardly projecting arm of the hammer-driving-lever 63. It will of course be understood that there is a hammer and hammer-driving-lever and spring and latch or trigger in each order of the machine, and that the bail cross-rod 66 is common to the entire series of hammer-driving-levers. Furthermore the familiar expedient is employed which consists in forming the latches or triggers with laterally turned tail-pieces 67^a so that a higher order latch will trip the next adjacent lower order latch for the filling in of ciphers to the right of the highest significant digit in a printed amount.

The bail cross-rod 66 is carried between a pair of side-plates 69 secured to the rock-shaft 64 upon which the hammer-driving-levers are pivoted. This bail structure besides operating to retract the hammer-driving-levers also serves to trip the triggers. Each of the latter has an arm 67^b pivoted to its lower extremity and drawn upward by a spring 67^c. This arm has a catch projec-

tion 67^d supplying a rearwardly-facing shoulder, and there is mounted in arc-shaped slots of the fixed supporting plates 70, a bar 71 adapted to coact with such shoulder to trip the trigger. This bar is common to all 70 of the triggers and it is operated by the before-identified bail structure. The slots in which the bar works are struck on an arc about the center of the bail rock-shaft 64 and the bail side-pieces 69 have upper rearwardly projecting arms 69^a which act upon the upper edge of the bar 71 at the proper time to cause said bar to trip any of the triggers whose arms 67^b have been elevated into the path of movement of the bar. Springs 80 72 retract the bar and furthermore the bail side-pieces 69 have lower rearwardly projecting arms 69^b to act upon the under edge of the bar and insure its return to the normal upper position shown in Fig. 1. It will 85 be observed that in Fig. 2 where the handle of the machine is at the limit of its forward movement the bail structure is shown rocked upward as to that portion in front of the rock-shaft 64 and downward as to the arms 90 69^a, so that the latter have driven the bar 71 downward and forward and the trigger which appears in that view has been tripped and the hammer fired.

The above-described hammer action is in 95 general a familiar one and I have simply chosen it in the present instance as one readily capable of adaptation to the needs of the novel type system above described. It is a well-known expedient to control the triggers by the type-carriers of the respective orders for the purpose of preventing the printing of ciphers to the left of the highest significant digit, and this is commonly accomplished in a hammer action of the above-described character by co-operatively relating the type-carriers to trigger-arms such as 67^b. I follow that plan in the present instance and the novelty of my invention in this connection consists in providing for the 100 suppression of the trigger-tripping means or disablement of the triggers, both when ciphers are at the printing line under straight adding conditions and when ciphers are at the printing line under subtracting 105 conditions. Manifestly this accomplishment calls for material modification of or addition to the known hammer action because when ciphers are at the printing line in subtracting, the type-carriers are in their uppermost positions, whereas when ciphers are at the printing line in adding the type-carriers are in their lowermost positions. Fig. 1 shows the units type-carrier in its lowest position with the addition cipher at the 110 printing line. (The tens type-carrier beyond is indicated by the dotted line, also in lowest position, and incidentally the 9-type of the tens type-carrier is disclosed by reason of the blank space between the cipher 115 120 125 130

type of the units type-carrier and the 1-type thereof in the addition series.) Fig. 2, which like Fig. 1 illustrates the machine in adding condition, shows the tens-type-carrier with the 3-type of the addition series at the printing line. Fig. 3, which illustrates the machine in subtracting condition, shows the tens type-carrier with its 4-type of the subtraction series at the printing line, and here the tens type-carrier is broken away to disclose the hundreds type-carrier with the cipher type of its subtraction series at the printing line. These three views serve to illustrate the control of type-carriers over triggers both under adding and under subtracting conditions.

Referring first to Fig. 1, a long irregular-shaped lever 80 is pivoted intermediate its ends upon a cross-rod 81 a short distance forward of the cross-rod 68 on which the triggers are pivoted. The rearwardly curved lower arm of this lever is carried up alongside a rearward extension of the trigger arm 67^b and has a laterally turned end portion which engages over that extension. This lower arm of the lever is normally held forward by a bail cross-rod 82 occupying slots in the frame-plates 70, and the engaged trigger-arm is held down with its catch 67^a below the path of travel of the tripping bar 71, as shown in Fig. 1. In every operation of the machine the bail cross-rod 82 is swung back and forward, and it moves back to free the lever arm just before the tripping bar 71 is operated, in order that the trigger arm 67^b may rise in time to be operated upon by said bar. Whether or not that trigger-arm rises will depend upon the position of the associated type-carrier. The upper arm of the controlling lever has a forwardly projecting foot 80^a at a point intermediate its length, and the associated type-carrier has a leg 52^b with a laterally turned extremity which normally stands immediately in front of the said lever foot 80^a, as shown in Fig. 1. Consequently if the type-carrier does not rise the lever is blocked notwithstanding the retreat of the bail cross-rod 82, and so the trigger-arm will not be permitted to rise and the advance of the tripping-bar 71 will not affect it. This much corresponds in general with the familiar control of printing hammers in machines of this character, and it will of course be understood that the rise of the type-carrier for the printing of any significant digit takes the extremity of the leg 52^b upwardly beyond the foot 80^a so that the trigger-arm will rise into the path of the tripping-bar 71 and the trigger will be tripped as shown in Fig. 2.

Now, as before pointed out, when a cipher occurs in the subtrahend the corresponding rack-bar and type-carrier partake of maximum movement. This brings the lower-most type, to-wit, the cipher type of the sub-

traction series, to the printing line. It should of course be printed and will be through the tripping of one trigger by another, but it must be borne in mind that 9's are required to be added complementally in all orders higher than that where the highest significant digit of the subtrahend occurs, in order that a clear remainder may be registered. This means of course that all type-carriers of such higher orders will partake of maximum movement and present their types at the printing line but manifestly these should not print. Therefore I provide for controlling the triggers by the type-carriers in the matter of subtraction cipher printing upon the same principle as in connection with addition cipher printing but through a reversed relationship. That is to say, the type-carriers impose no restraint upon the trigger-arms when said type-carriers are at their lowest positions in subtraction, whereas they do impose restraint upon said arms when the type-carriers are at their highest positions in subtraction. It should first be noted that the lifting of the pivot-rod 50 of the type-carriers lifts the extremities of the type-carrier legs 52^b above the lever feet 80^a. Next it should be noted that each of these control levers extends upward beyond the foot 80^a to a point where it may coact with the extremity of the type-carrier leg when the type-carrier is at its highest position, as shown by dotted lines in Fig. 3. The lever has a forwardly turned arm 80^b at its upper end which terminates in an upwardly projecting finger 80^c designed to function the same as the foot 80^a. Thus when the type-carrier is in its highest position, as in the case of the hundreds type-carrier illustrated in Fig. 3, the laterally turned extremity of the foot 52^b is directly in front of this finger 80^c and blocks the lever so that it will continue to restrain the trigger-arm. At all intermediate positions of the type-carrier the lever will not be blocked nor the trigger-arm restrained, as in the case of the tens type-carrier illustrated in Fig. 3, which stands at the position for the printing of 4 as a digit of the subtrahend.

It should perhaps be noted at this point that in the case of a cipher occurring in the units order of the subtrahend the rack-bar moves ten steps so as to provide for imparting a complete rotation to the units wheel, and correspondingly the units type-carrier rises ten steps. Inasmuch as the units type-carrier must move a step farther than the higher order type-carriers in order to bring its cipher to the printing line the upper arm of the controlling lever 80 in the units order is somewhat longer than the upper arms of the levers in the higher orders, as illustrated in Fig. 1.

It should perhaps be further noted that

the act of setting the machine for subtraction brings the 9-types of the subtraction series to the printing line, except that of the units type-carrier, and it will be recalled that when a 9-key is depressed in the setting up of a subtraction the rack-bar is prevented from moving, except in the case of the units rack-bar, and so the 9-type is held at the printing line. Now in the case of the units type-carrier there is a one-step movement upward to bring this 9-type of the subtraction series to the printing line.

Referring finally to the actuating devices worked by the operating lever 17, and best shown in Fig. 8, the lower arm 17^a of such lever has a stud 17^b occupying an open slot in the rear end of a link 90 with which said lever arm is connected by a spring 91. 92 designates a power spring connecting the lever arm with the base of the machine. The purpose of the other spring 91 is to provide a yielding connection to protect the mechanism in case of a lockup. Said link 90 is pivotally connected at its forward end to a bell-crank lever 93, which has a rearwardly extending arm with a down-turned branch 93^a formed with a long cam-slot 93^b for operating a rack-bar restoring bail. 94 designates the side-pieces of said bail one of which carries a roller stud 94^a occupying the said cam-slot, and 94^b designates the cross-rod of the bail which works in slots of the frame sides and acts against arms 15^b of the rack-bars. As the handle is drawn forward the said bail is swung rearwardly. There is a suitable dwell to provide for the printing, and when the operating lever returns, the bail is swung forward to restore rack-bars and type-carriers.

Another link 95 also pivotally connected to the bell-crank 93 extends rearwardly and pivotally connects with one arm 96 of another bell-crank lever secured to the rock-shaft 64 of the bail structure before-described as functioning to trip hammer-triggers and to restore hammers. It will be apparent that this bail structure derives its rocking movement from the operating handle through the medium of the link 95.

The arm 96 of this bell-crank on the rock-shaft 64 further functions to retract the bail cross-rod 82. The side-pieces of this bail are designated by the numeral 82^a and one of them has a rearwardly extending arm 82^b with a roller stud engaging a segmental head formed on the bell-crank arm 96. At the forward end of this head there is a cam rise 96^a. A spring 82^c draws the bail forward but as the bell-crank arm 96 nears the end of its rearward movement (as derived from the forward stroke of the operating handle) said cam-rise acts upon the roller stud of the arm 82^b rocking the bail so as to retract its cross-rod 82 and

thereby free the several controlling levers 80.

The last-mentioned bell-crank has still a further function to perform, to wit, that of automatically releasing depressed keys. To this end its other arm 96^c is connected by a link 97 with a crank-arm 98 on a rock-shaft 99 which carries a series of arms 100 to which are pivoted respectively small bell-crank 101 to act upon the detent strips 24. Each of these small bell-crank is connected by a spring 102 to a branch of the associated arm 100 which spring normally holds a stud on the small bell-crank against a shoulder of the arm 100, as shown in Figs. 1 and 8. There is a roller 103 at the end of the forwardly projecting arm of the bell-crank 101 which roller normally underlies the projecting rear end of the detent strip. When the handle is drawn forward and the rock-shaft 99 rotated clockwise, the spring 102 yields and the said roller travels idly up past the end of the detent strip. The small bell-crank then recovers its position and swings on up with its supporting arm 100 to the position illustrated in Fig. 2. Then when the operating handle returns, under the power of the spring 92, and the rock-shaft 99 is correspondingly turned counterclockwise, the small roller 103 will strike against the end of the detent strip and force it forward thereby releasing any depressed key.

As before stated any suitable means may be employed to properly control the engagement of the registering pinions 12^a with the racks 14^a. I have here shown a reciprocating bar 105 for such purpose, this bar being slotted to embrace the pivot stud of the bell-crank 93 for guiding purposes and having a cam-slot 105^a embracing the shaft 105 or rod on which the pinions turn. The bar is reciprocated by the action of cams 93^a and 93^b on the bell-crank 93, against studs 105^b and 105^c carried by bar. At the end of the forward stroke of the operating handle the cam 93^a acts against the stud 105^b forcing the bar rearward and thereby meshing the pinions with the racks. At the end of the return movement of the operating handle the cam 93^b acts upon the stud 105^c and drives the bar forward disengaging the pinions from the racks.

I have omitted illustration of carrying mechanism because nothing unique is required in this respect and any one of a number of known forms of carrying mechanism may be employed. Neither have I extended the illustration to zeroizing or total printing mechanism. Known principles are applicable here also, such as that involving release of all rack bars and reverse rotation of registering wheels to zero whereby movement of rack bars is measured and

type-carriers correspondingly set,—of course with the machine in adding condition, except in case of an overdraft, which would call for printing the complement of the registration on the wheels. By reason of my novel form of type-carriers the correct printing of an overdraft or a negative total can be accomplished by simply keeping the machine in subtracting condition while 5 practising the familiar totaling operation.

I claim:

1. In an adding machine, the combination of a series of value keys; two sets of stops complementally settable by said keys; and 15 a differentially movable registering element carrying alternating stop members to separately coact with the key stops of the two sets, the setting of one such member to coact with the key stops of one set entailing dis- 20 ablement of the other member for coaction with the key stops of the other set, and the graduation of stops of the active set deter- 25 mining the extent of movement of the register- 30 ing element.
2. In an adding machine, the combination of a series of value keys; two sets of stops complementally settable by said keys; and a differentially movable registering element carrying a shiftable piece with alternating 35 stop members to separately coact with the key stops of the two sets.
3. In an adding machine, the combination of a series of value keys; two sets of stops complementally settable by said keys; and 40 a differentially movable registering element carrying a pivoted piece with alternating stop members to separately coact with the key stops of the two sets.
4. In an adding machine, the combination 45 of a column of depressible keys; two sets of independently movable stops; means for displacing said stops by said keys in pairs, each pair composed of a stop of each set complementally related to each other; and a differentially movable registering element carrying alternating stop members to separately coact with the key stops of the two sets, the setting of one such member to coact with the key stops of one set entailing dis- 50 ablement of the other member for coaction with the key stops of the other set, and the graduation of stops of the active set deter- 55 mining the extent of movement of the register- 60 ing element.
5. In an adding machine, the combination of a column of depressible keys; two sets of independently movable stops; means for displacing said stops by said keys in pairs, each pair composed of a stop of each set complementally related to each other; and a differentially movable registering element carrying a shiftable piece with alternating 65 stop members to separately coact with the key stops of the two sets.
6. In an adding machine, the combina-

tion of a column of depressible keys; two sets of independently movable stops; means for displacing said stops by said keys in pairs, each pair composed of a stop of each set complementally related to each other; and a differentially movable registering element carrying a pivoted piece with alternating stop members to separately coact with the key stops of the two sets. 70

7. In an adding machine, the combination of a column of keys; two sets of vertically arranged independently movable stop blades; cam bars operatively connected with the keys for shifting thereby and engaged with the stop blades in pairs thereof, each pair composed of a stop of each set complementally related to each other; a differentially movable registering element having a stop piece extending adjacent both sets of stop blades; and means for establishing co-operative relationship between said stop-piece and either set of stop blades. 75

8. In an adding machine, the combination of a column of keys; two sets of vertically arranged independently movable stop blades; cam bars operatively connected with the keys for shifting thereby and engaged with the stop blades in pairs thereof, each pair composed of a stop of each set complementally related to each other; and a differentially movable registering element having a stop-piece which is shiftable for coaction with either set of stop blades in 80 measuring movement of said element. 85

9. In an adding machine, the combination of a column of keys; two sets of vertically arranged independently movable stop blades; cam bars operatively connected with the keys for shifting thereby and engaged with the stop blades in pairs thereof, each pair composed of a stop of each set complementally related to each other; and a differentially movable registering element having a pivoted piece with stop projections to coact respectively with the two sets of 90 stop-blades. 100

10. In an adding machine, the combination of a column of keys; two sets of vertically arranged independently movable stop blades; cam bars operatively connected 115 with the keys for shifting thereby and engaged with the stop blades in pairs thereof, each pair composed of a stop of each set complementally related to each other and each bar coöperating with two such pairs in 120 alternation through reversed cam formations; a differentially movable registering element having a stop piece extending adjacent both sets of stop blades; and means for establishing coöperative relationship between said stop piece and either set of stop blades. 125

11. In an adding machine, the combination of a series of value keys; two sets of stops complementally settable by said keys; 130

- a differentially movable registering element adapted to have its movement measured by a key stop of either set; means for establishing coöperative relationship between either set of key stops and said registering element; a zero stop to normally prevent movement of the registering element under one such relationship; means common to the keys for withdrawing said zero stop; 10 an additional key of highest value; a fixed stop for measuring the movement of the registering element when that key is used under that same relationship; an additional stop set by said key to limit movement of 15 the registering element under the other or complemental relationship; and another fixed stop to measure the maximum movement of the said element under such complemental relationship when no one of the 20 keys is used.
12. In an adding machine, the combination of a column of keys; two sets of vertically arranged independently movable stop blades; cam bars operatively connected with 25 the keys for shifting thereby and engaged with the stop blades in pairs thereof, each pair composed of a stop of each set complementally related to each other; a differentially movable registering element having a 30 pivoted piece with stop projections to coact respectively with the two sets of stop blades; a zero stop blade to normally coact with one such projection and prevent movement of the registering element when no key is in 35 use; means common to the keys for withdrawing said zero stop blade; an additional key of highest value; a fixed stop for that same projection to encounter when said highest value key is used; an additional 40 stop blade set by said key for the other projection to encounter whereby to limit movement of the registering element; and another fixed stop for this projection to encounter whereby to measure maximum 45 movement of the registering element.
13. In an adding machine, the combination of a series of value keys; two sets of stops complementally settable by said keys; a differentially movable type-carrier coupled to said registering element and having 50 a double set of types, those of one set running in reverse order to those of the other and alternating therewith; and means for establishing coöperative relationship between either set of key stops and said registering element and for correspondingly and incidentally adjusting the type-carrier to preliminarily provide for bringing the proper one of its two sets of type into use. 55
14. In an adding machine, the combination of a series of value keys; two sets of stops complementally settable by said keys; a differentially movable pivoted type-carrier coupled to said registering element and having a double set of types, those of one 60
- set running in reverse order to those of the other and alternating therewith; and means for establishing coöperative relationship between either set of key stops and said registering element and for correspondingly locating the pivot of the latter to bring the proper one of its two sets of type into use. 70
15. In an adding machine, the combination of a series of value keys; two sets of stops complementally settable by said keys; 75 a differentially movable pivoted type carrier coupled to said registering element and having a double set of types, those of one set running in reverse order to those of the other and alternating therewith, and the 80 pivot of said type carrier being shiftable to provide for use of either set of type; and a pivotally mounted reciprocating stop piece for coacting with the key-stops to measure movement of the registering element and of 85 the type carrier on its pivot, said stop-piece being coupled to the type carrier and shiftable with the latter's pivot whereby to establish coöperative relationship with the proper set of key stops. 90
16. In an adding machine, the combination of a series of value keys; two sets of stops complementally settable by said keys; a reciprocating registering rack bar; a stop piece pivotally mounted upon said rack bar 95 and having separated projections one for coaction with key stops of one set and the other for coaction with key stops of the other set; and a pivoted type carrier coupled to said stop piece and having a double set 100 of types those of one set running in reverse order to those of the other and alternating therewith, and the pivot of said type carrier being shiftable to provide for use of either set of types according to the accompanying setting of the stop-piece for coaction with one or another of the sets of key stops. 105
17. In an adding machine, the combination of a number of denominational series 110 of keys, the keys of each series representing progressing numerical values; type carriers having corresponding types and also cipher types in double series reversely and alternately arranged; printing devices coöperatively related for the filling in of ciphers to the right of any significant digit, with provisions for preventing the printing of ciphers to the left thereof with type carriers at normal or at maximum displacement; differentially movable registering elements coupled to the type carriers respectively; complemental stop devices for indexing said registering elements and type-carriers under control of the keys; and means 115 for predetermining the character of coaction between said stop devices and said registering elements and correspondingly predetermining which series of types shall 120 serve. 125
- 130

18. In an adding machine, the combination of a number of denominational series of keys, the keys of each series representing progressing numerical values; type carriers having corresponding types and also cipher types in double series reversely and alternately arranged; printing hammers; triggers therefor; trigger tripping means; devices controlled by the type carriers for disabling said latter means when cipher types of either series are at printing position; means whereby triggers may be tripped independently of the said devices for the filling in of ciphers to the right of significant digits; differentially movable registering elements coupled to the type carriers respectively; complemental stop devices for indexing said registering elements and type carriers under control of the keys; and means for predetermining the character of coaction between said stop devices and said registering elements and correspondingly predetermining which series of types shall serve. 10
19. In an adding machine, the combination of a number of denominational series of keys, the keys of each series representing progressing numerical values; type carriers having corresponding types and also cipher types in double series reversely and alternately arranged; printing hammers; triggers therefor; trigger tripping means comprising a reciprocating element and displaceable trigger-arms operated upon thereby; devices controlled by the type carriers for holding said trigger arms displaced when cipher types of either series are at printing position; means whereby triggers may be tripped independently of the said devices for the filling in of ciphers to the right of significant digits; differentially movable registering elements coupled to the type carriers respectively; complemental stop devices for indexing said 20 registering elements and type carriers under control of the keys; and means for predetermining the character of coaction between said stop devices and said registering elements and correspondingly predetermining which series of types shall serve. 25
20. In an adding machine, the combination of a number of denominational series of keys, the keys of each series representing progressing numerical values; type carriers having corresponding types and also cipher types in double series reversely and alternately arranged; printing hammers; triggers therefor; trigger-tripping means comprising a reciprocating element and displaceable trigger-arms which tend to assume positions where said element will act upon them; levers engaged with said arms respectively to restrain them and having spaced projections, the type-carriers having coacting projections; means whereby triggers may be tripped independently of said swinging members for the filling in of ciphers to the right of significant digits; differentially movable registering elements coupled to the type carriers respectively; complemental stop devices for indexing said 30 35 40 45 50 55 60 65 70 75 80 85 90 95 100 105 110 115 120 125 130
18. In an adding machine, the combination of a number of denominational series of keys, the keys of each series representing progressing numerical values; type carriers having corresponding types and also cipher types in double series reversely and alternately arranged; printing hammers; triggers therefor; trigger-tripping means comprising a reciprocating element and displaceable trigger-arms which tend to assume positions where said element will act upon them; levers engaged with said arms respectively to restrain them and having spaced projections, the type-carriers having coacting projections; means whereby triggers may be tripped independently of said swinging members for the filling in of ciphers to the right of significant digits; differentially movable registering elements coupled to the type carriers respectively; complemental stop devices for indexing said 70 75 80 85 90 95 100 105 110 115 120 125 130
19. In an adding machine, the combination of a number of denominational series of keys, the keys of each series representing progressing numerical values; type carriers having corresponding types and also cipher types in double series reversely and alternately arranged; printing hammers; triggers therefor; trigger-tripping means comprising a reciprocating element and displaceable trigger-arms which tend to assume positions where said element will act upon them; levers engaged with said arms respectively to restrain them and having spaced projections, the type-carriers having coacting projections; means whereby triggers may be tripped independently of said swinging members for the filling in of ciphers to the right of significant digits; differentially movable registering elements coupled to the type carriers respectively; complemental stop devices for indexing said 70 75 80 85 90 95 100 105 110 115 120 125 130
20. In an adding machine, the combination of a number of denominational series of keys, the keys of each series representing progressing numerical values; type carriers having corresponding types and also cipher types in double series reversely and alternately arranged; printing hammers; triggers therefor; trigger-tripping means comprising a reciprocating element and displaceable trigger-arms which tend to assume positions where said element will act upon them; levers engaged with said arms respectively to restrain them and having spaced projections, the type-carriers having coacting projections; means whereby triggers may be tripped independently of said swinging members for the filling in of ciphers to the right of significant digits; differentially movable registering elements coupled to the type carriers respectively; complemental stop devices for indexing said 70 75 80 85 90 95 100 105 110 115 120 125 130

- indexing said registering elements and type-carriers under control of the keys; and means for predetermining the character of coaction between said stop devices and said 5 registering elements and correspondingly predetermining which series of types shall serve.
23. In an adding machine, the combination of a number of denominational series 10 of keys, the keys of each series representing progressing numerical values; type-carriers having corresponding types and also cipher types in double series reversely and alternately arranged; printing devices coöperatively related for the filling in of ciphers to the right of any significant digit, with provisions for preventing the printing of ciphers to the left thereof with type-carriers at normal or at maximum displacement; differentially movable registering elements coupled to the type-carriers respectively; two sets of stops for each series of keys complementally settable by the keys other than that of highest value; a stop-piece 15 on each registering element settable in conjunction with the associated type-carrier for coaction with either set of key-stops; a zero-stop for each registering element to normally prevent movement thereof under one setting of such stop-piece; means common to all the keys of a series for withdrawing said zero-stop; a fixed stop for measuring the movement of each registering element when the key of highest value is used under that same setting of stop-piece; an additional stop set by said key to limit movement of the registering element under the other or complemental setting of the stop-piece; and an 20 other fixed stop for each registering element to measure the maximum movement thereof under such complemental setting of stop-piece when no key of the series is used.
24. In an adding machine, the combination of a number of denominational series 45 of keys, the keys of each series representing progressing numerical values; type-carriers having corresponding types and also cipher types in double series reversely and alternately arranged, said type-carriers being 50 mounted on a shiftable pivot rod; printing hammers; triggers therefor; trigger-tripping means comprising a reciprocating element and displaceable trigger-arms which tend to assume positions where said element 55 will act upon them; levers engaged with said arms respectively to restrain them, and having spaced projections, the type-carriers having coacting projections; means for normally holding said levers in restraining position and freeing them prior to advance of the reciprocating trigger-tripping element; means whereby triggers may be tripped independently of said levers for the filling in of ciphers to the right of significant digits; 60 registering rack-bars; pivoted stop-arms on the same having spaced stop-projections, said arms being coupled to the type-carriers respectively; two sets of stop-blades for each series of keys complementally settable 65 by the keys other than that of highest value and adapted to coact with said spaced stop-projections respectively; zero-stops to normally prevent movement of rack-bars under one setting of their stop-arms; means 70 common to keys by series for withdrawing the zero-stops; fixed stops for measuring maximum movement of rack-bars under that same setting of stop arms; additional stops set by the keys of highest value to limit 75 movement of rack-bars under the other or complemental setting of stop-arms; and fixed stops to measure maximum movement of rack-bars under that setting of stop-arms when no keys are used.

ALLEN A. HORTON.
